THREE-WAY DENTAL SYRINGE

George F. Bueckle, 1021 Laguna Ave.,
Burlingame, Calif. 94010

Filed Mar. 16, 1973, Ser. No. 342,273

Term of patent 14 years

Int. Cl. D24—01

U.S. Cl. D24—1 D

FIG_1

FIG_2

FIG_4

FIG_3

FIG_5

FIG. 1 is a perspective view of the three-way dental syringe embodying my new design;

FIG. 2 is a top plan view of the three-way dental syringe of FIG. 1;

FIG. 3 is a side view of the three-way dental syringe of FIG. 1;

FIG. 4 is a rear view of the three-way dental syringe of FIG. 1; and

FIG. 5 is a front view of the three-way dental syringe of FIG. 1.

I claim:

The ornamental design for a three-way dental syringe, as shown.
